(57) **CLAIM**

The ornamental design for a magnifier device, as shown and described.

DESCRIPTION

FIG. 1 is a front view of the magnifier device according to the present invention.

FIG. 2 is a rear view of the magnifier device of FIG. 1.

FIG. 3 is a left side view of the magnifier device of FIG. 1.
FIG. 4 is a right side view of the magnifier device of FIG. 1.

FIG. 5 is a top view of the magnifier device of FIG. 1.

FIG. 6 is a bottom view of the magnifier device of FIG. 1.
FIG. 7 is a perspective view of the magnifier device according to the present invention.

FIG. 8 is a left side view of the magnifier device of FIG. 1 in an alternate configuration; and,

FIG. 9 is a rear view of the magnifier device of FIG. 1 in an alternate configuration.
